CLAIM

The ornamental design for an underground irrigation equipment protective device, as shown and described.

DESCRIPTION

FIG. 1 is a top-front-left perspective view of an underground irrigation equipment protective device showing my new design;

FIG. 2 is a detailed view of section 2 of FIG. 1;

FIG. 3 is bottom-rear-right view thereof;

FIG. 4 is a front elevational view thereof;

FIG. 5 is a rear elevational view thereof;

FIG. 6 is a left-side elevational view thereof;

FIG. 7 is a right-side elevational view thereof;

FIG. 8 is top plan view thereof;

FIG. 9 is a detailed view of section 9 of FIG. 8; and,

FIG. 10 is a bottom plan view thereof.

The dot-dash-dot broken lines denote the boundaries of the detail areas and detail views and forms no part of the claim.

1 Claim, 10 Drawing Sheets
